FIG. 2

INVENTOR.

BY John Leech

Worster & Danis ATTORNEYS.

UNITED STATES PATENT OFFICE.

JOHN LEECH, OF BRIDGEPORT, CONNECTICUT, ASSIGNOR TO INTERNATIONAL SILVER COMPANY, OF MERIDEN, CONNECTICUT, A CORPORATION OF NEW JERSEY.

DESIGN FOR A FORK OR SIMILAR ARTICLE.

Application filed August 21, 1922. Serial No. 3,486. Term of patent 7 years.

To all whom it may concern:

Be it known that I, JOHN LEECH, a citizen of the United States, residing at Bridgeport, county of Fairfield, State of Connecticut, have invented a new, original, and ornamental Design for a Fork or Similar Article, of which the following is a specification, reference being had to the accompanying drawing, forming a part thereof.

In the drawing—

scale of a fork, a spoon being shown in dotted lines, showing my new design.

I claim—

The ornamental design for a fork or similar article substantially as shown.

In testimony whereof I affix my signature.

JOHN LEECH.
